Primary Examiner — Elizabeth J Oswecki(74) *Attorney, Agent, or Firm* — Fitch, Even, Tabin & Flannery LLP(57) **CLAIM**

The ornamental design for an insole, as shown and described.

DESCRIPTION

FIG. 1 is a front perspective view of an insole showing my new design for use on the left foot;

FIG. 2 is a bottom plan view of the insole of FIG. 1;

FIG. 3 is a top plan view of the insole of FIG. 1;

FIG. 4 is a right side elevation view of the insole of FIG. 1;

FIG. 5 is a left side elevation view of the insole of FIG. 1;

FIG. 6 is a front elevation view of the insole of FIG. 1; and,

An insole for use on the right foot will have views which are mirror images of FIGS. 1-7.

The broken lines shown in the drawings represent portions of the insole that form no part of the claimed design.

1 Claim, 4 Drawing Sheets(56)
